US0D1086861S

(12) **United States Design Patent** (10) Patent No.: **US D1,086,861 S**
 (45) Date of Patent: ** Aug. 5, 2025

- (54) **REINFORCING BAR FOR ANGLE**
- (71) Applicant: **Speedrack Co., Ltd.**, Gimpo-si (KR)
- (72) Inventors: **Hyo Sang Yoon**, Gimpo-si (KR); **Yoon Ki Kim**, Incheon (KR); **Jae Koon Han**, Gimpo-si (KR); **Jun Hyuk Lee**, Seoul (KR); **Heon Woo Jo**, Pohang-si (KR)
- (73) Assignee: **SPEEDRACK CO., LTD.**, Gimpo-si (KR)

(**) Term: **15 Years**

(21) Appl. No.: **29/908,955**

(22) Filed: **Jan. 16, 2024**

(30) **Foreign Application Priority Data**

- Jul. 18, 2023 (KR) 30-2023-0027621
